UNITED STATES PATENT OFFICE

EUGENE I. PAYNE, OF CHICAGO, ILLINOIS
DESIGN FOR TYPE OR SIMILAR ARTICLE

Application filed April 25, 1932. Serial No. 43,606. Term of patent 3½ years.

To all whom it may concern:

Be it known that I, EUGENE I. PAYNE, a citizen of the United States, residing at Chicago, in the county of Cook and State of Illinois, have invented a new, original, and ornamental Design for Type or Similar Article, of which the following is a specification, reference being had to the accompanying drawing, forming part thereof.

The characteristic feature of the design resides in the contour of the article to be used as a spade symbol on playing cards and is

intended for use not only in the printing of playing cards but also for the representation of the spade symbol in connection with the printing of books, newspapers, etc.

While the drawing discloses the design in outline it may be filled in and appear entirely in black or in color.

I claim:

The ornamental design for type or similar article substantially as shown and described.

EUGENE I. PAYNE.
